FIG. 1 is a front perspective view of a ski for a snow vehicle in accordance with a first embodiment of the design;
 FIG. 2 is a front elevation view of the ski of FIG. 1;
 FIG. 3 is a rear elevation view of the ski of FIG. 1;
 FIG. 4 is a right side elevation view of the ski of FIG. 1;
 FIG. 5 is a left side elevation view of the ski of FIG. 1;
 FIG. 6 is a top view of the ski of FIG. 1;
 FIG. 7 is a bottom view of the ski of FIG. 1;
 FIG. 8 is a front perspective view of a ski for a snow vehicle in accordance with a second embodiment of the design;
 FIG. 9 is a front elevation view of the ski of FIG. 8;
 FIG. 10 is a rear elevation view of the ski of FIG. 8;
 FIG. 11 is a right side elevation view of the ski of FIG. 8;
 FIG. 12 is a left side elevation view of the ski of FIG. 8;
 FIG. 13 is a top view of the ski of FIG. 8;
 FIG. 14 is a bottom view of the ski of FIG. 8;
 FIG. 15 is a front perspective view of a ski for a snow vehicle in accordance with a third embodiment of the design;
 FIG. 16 is a front elevation view of the ski of FIG. 15;
 FIG. 17 is a rear elevation view of the ski of FIG. 15;
 FIG. 18 is a right side elevation view of the ski of FIG. 15;
 FIG. 19 is a left side elevation view of the ski of FIG. 15;
 FIG. 20 is a top view of the ski of FIG. 15;
 FIG. 21 is a bottom view of the ski of FIG. 15;
 FIG. 22 is a front perspective view of a ski for a snow vehicle in accordance with a fourth embodiment of the design;
 FIG. 23 is a front elevation view of the ski of FIG. 22;
 FIG. 24 is a rear elevation view of the ski of FIG. 22;
 FIG. 25 is a right side elevation view of the ski of FIG. 22;
 FIG. 26 is a left side elevation view of the ski of FIG. 22;
 FIG. 27 is a top view of the ski of FIG. 22; and,
 FIG. 28 is a bottom view of the ski of FIG. 22.
 The broken lines depict environment subject-matter only and do not form part of the claimed design.
